(57) **CLAIM**

The ornamental design for a juice pressing device, as shown and described.

DESCRIPTION

FIG. 1 is a perspective view of a juice pressing device of our new design.

FIG. 2 is a front view of the juice pressing device of our new design.

FIG. 3 is a rear view of the juice pressing device of our new design.

FIG. 4 is a left view of the juice pressing device of our new design.

FIG. 5 is a right view of the juice pressing device of our new design.

FIG. 6 is a top view of the juice pressing device of our new design; and,

FIG. 7 is a bottom view of the juice pressing device of our new design.

The broken lines shown illustrate portions of the juice pressing device that form no part of the claimed design.

1 Claim, 7 Drawing Sheets
